UNITED STATES PATENT OFFICE.

FRANK G. MARBACH AND MARTHA P. MARBACH, OF CLEVELAND, OHIO.

WASHING MACHINE AND WRINGER.

Application filed October 6, 1923. Serial No. 666,928.

The present invention relates to an improvement in washing machines, and more particularly to an improvement in power operated wringers for use in connection with 5 compartmented laundry trays such for example as shown in our pending application Serial No. 540,733, filed Mar. 3, 1922, of which this application is in part a continuation. One of our objects is to provide a 10 wringer operated by power and adapted to be readily controlled to safeguard the operator and all working operations, and another object involves the mounting of a clothes wringer in a movable or slidable 15 position upon the tub or tray and in operable connection with a motor, whereby washing of the goods may take place in one compartment and rinsing and wringing operations may be successively carried on step by step 20 with facility and despatch by shifting the wringer to other compartments of the tub or tray.

In the accompanying drawings, Fig. 1 is a perspective view of a wash tub or tray 25 and wringer mechanism constructed according to our invention. Fig. 2 is a cross section of the same tub on line 2—2 of Fig. 5, showing the wringer in the background. Fig. 3 is a top view of the tub or tray and the 30 wringer. Fig. 4 is a top view of the skeleton-supporting frame for the tub or tray, including the motor and pump mechanism mounted thereon. Fig. 5 is a vertical section longitudinally of the tub or tray and the 35 wringer on line 5—5 of Fig. 3, and a front view of the skeleton supporting frame and parts mounted thereon. Fig. 6 is an enlarged detail view partly in section of the driving parts associated with the motor. 40 Fig. 7 is a perspective view of the tub or tray and wringer removed from the skeleton supporting frame, and Fig. 8 is a perspective view of said supporting frame. Fig. 9 is a top view of the wringer with 45 parts thereof in section and Fig. 10 is a side view of the wringer, also with portions thereof in section including the telescopic power transmitting shaft. Figs. 11 and 12 are cross sections of the wringer on line 50 12—12 of Fig. 10, showing the wringer in open and closed positions. Fig. 13 is a cross section on line 13—13 of Fig. 10 showing the telescopic shaft and its telescopic 55 housing.

The invention comprises an elongated re-

ceptacle, tub or wash tray 2, which is made of concrete and made with two transverse division walls 3 and 4 to provide three separate washing compartments 5, 6 and 7, respectively. The rear wall 8 is common to 60 all these compartments and rises to the same elevation as the division walls and supports separate hot and cold water faucets 9. Drain outlets 10 are also provided which are connected up in any suitable way to a single 65 discharge pipe, and a washing and agitating device is incorporated in one of the compartments, which device may be of any suitable kind but as exemplified in the drawings 70 consists of an air distributing and agitating device comprising a series of radiating pipes 11 embedded within the concrete bottom 12 of compartment 5. These pipes terminate in vertical nipples 13 having relatively small outlets, and the several pipes 11 75 branch from a common air intake connection 15 which extends rearwardly from the tray or tub where a U-shaped pipe 19 is detachably secured thereto.

An air pump 21 located beneath the tray 80 has a pipe connection with the bottom end of U-member 19 which extends upwardly outside of the rear wall above the normal level of the body of water therein so that the water is trapped and cannot flow back 85 through these pipes to the pump, which pump may be of the rotary type or any other kind capable of producing and delivering a continuous flow of air of six to eight 90 cubic feet per minute through the relatively small pipes 15 and 19. Pump 21 is driven by a shiftable belt 23 from a pulley P on the armature shaft of an electric motor M, and a belt shifting device 23 is provided, which is controlled by a hand lever 24 95 pivotally mounted upon a bracket affixed to the skeleton supporting frame F for the wash tray.

Motor M is also arranged to operate a wringer 26 which is supported to slide or 100 roll upon the parallel upper edges of the rear and front walls of the wash tray, the operating connections between the motor and the wringer being located at the rear side of the tray. Thus, a friction clutch 27 is adapted to connect and disconnect the motor shaft from a separate motor shaft extension 27' having a worm pinion 28 meshing with a worm gear 29 upon the lower end of a telescopic extensible shaft 105 110.

30. The upper and lower sections of shaft 30 are journaled in separate swiveled brackets 31 and 32, respectively, and a bevel gear 33 for the upper shaft section meshes 5 with a similar gear 34 at the rear end of a jointed horizontal shaft 35 carrying the upper rubber roller 36 of the wringer. Shaft 35 is partly journaled in and supported by a vertical bracket 37 and partly 10 by upright standards 40 and 41 rigidly mounted upon a slidable or movable base member 43.

The wringer is mounted on base member 43 at an inclination relative to the cross 15 walls of the tray so that it may be stationed obliquely in front of the operator for greater convenience in entering the goods between the wringer rollers and in controlling the operations of the wringer. In 20 operations the wringer is usually stationed directly above one or the other of the two division walls of the tray where the transfer of goods may be readily effected from one compartment to the other, and it is also 25 readily shifted lengthwise across the compartments to either end of the tray. The upright standards 40-41 are joined together by an inclined delivery board 39 and have curved overhanging ends within 30 which shaft 35 has rotatable bearing. The end portions 42 of the wringer base are extended for stability and have rollers adapted to ride upon the longitudinal edges of the tray, and a thumb or hand screw 38 serves 35 to lock the wringer against movement upon the tray.

The lower rubber roller 50 of the wringer is mounted upon a shaft 51 which is free 40 to rotate and also to slide vertically within limits in slotted supporting arms 52 which are pivotally attached or hinged at 53 upon standards 40 and 41. These arms are rigidly united at their front ends by a feed board 49, and each has a hollow box or 45 dependent portion 54 within which a coiled compression spring 55 is confined and adapted to exert an upward pressure on a slidable bearing block for the roller shaft 51. A tightening or tension screw 56 bears 50 against the bottom end of each spring and extends through the lower end of each box 54 where it can be reached and turned when occasion requires. However, arms 52 and lower roller 50 are free to drop away from 55 the upper roller 36 unless supported by a pivoted locking member 57 in the form of a bail or handle having hooks or catches 58 adapted to interlock with projections 59 on arms 52, see Fig. 6. This handle or bail 57 60 has side arms loosely sleeved upon upper shaft 35 at each end of the wringer, and the lower roller can be caused to drop away from the upper roller by gravity by pressing the cross piece rearwardly either by the 65 hand, forearm, elbow or even the head. In

this way instant release may be effected of the goods and the strain on the wringer relieved when a thick fold of goods is passing between the rollers, or in the event that the hair, hands or fingers of the operator are 70 caught with the goods and drawn toward the rollers.

A further important safe-guard is provided, however, to avoid accident and injury to the machine and operator. Thus, this wringer is particularly designed to operate only when clutch 27 is in driving connection with motor M, a condition which can only be maintained by the operator alone. That is to say, when the operator is using the 80 wringer it is necessary for the operator to depress a pivoted pedal 60 extending lengthwise of the tray. The wringer is in action only when this pedal is down, the pedal being connected with the clutch and also provided with a spring 61 which shifts the pedal normally to throw out the clutch the moment the operator relieves the foot pressure upon the pedal. Consequently, if either or both hands are caught or endangered the 90 operator can cut off the power and stop the wringer instantly by merely relieving the foot pressure on the treadle.

In a washing operation the goods are placed in the first compartment 5 which has 95 been filled to a suitable height with water containing soap or any other cleansing agent, and a cover 62 either conical or flat, is placed over the compartment but spaced apart from the goods within the water. The electric 100 motor having been switched on, it is only necessary then to shift the belt by lever 24, whereupon a continuous stream of air is pumped into the bottom of a compartment 5 where it is compelled to pass upward 105 through the water wherever liberated at the perforation 13. Only a few such perforations are used and these are spaced widely apart, one at the middle and one near each corner of the compartment. As a result the 110 water and goods are constantly agitated; the presence of the goods prevents the air from escaping on straight vertical lines through the water; the distribution of the air and the changing lines of force tend to move and shift the goods from place to place and to rub the folds of the goods together with frictional cleansing effect; foam and suds gather on the surface beneath the cover and the turbulent water disseminates it 115 through the goods which rise and appear on the surface; and a thorough and complete cleansing of the goods is obtained in a very short time. During this operation the wringer may be clamped to the tray above 120 division wall 3, so that at the end of the operation the goods may, if desired, be passed through the wringer to the middle compartment. When the goods have been 125 discharged into second compartment 6 by 130

the wringer and rinsed or otherwise treated in middle compartment 6, the wringer is shifted to the opposite end above division wall 4 where the wet goods may be again passed through the wringer into compartment 7 preliminary to final wringing and drying operation. This last mentioned operation is performed after the wringer has been shifted to the extreme end of the tray 10 where it may be fixed in an overhanging discharge position above a wash basket. Washing and rinsing operations in the separate compartments and the wringing of goods may proceed simultaneously. That is to say, 15 while a batch of goods is being washed in the first compartment, another batch of goods may be undergoing a rinsing operation in the second compartment, while the operator is passing rinsed goods through the wringer 20 into the third compartment. A foldable extension F' is also provided at one end of the skeleton frame to seat a wash basket or other receptacle for the goods underneath the wringer when shifted to that end of 25 the tray.

In shifting the wringer the extensible shaft 30 at the rear of the tray telescopes and swings to different angles without disconnecting the wringer from the source of power, although when the operator releases the foot pressure on the treadle and the treadle spring throws out clutch 27, the wringer is brought to an instant stop by means of brake mechanism comprising a 35 disk 65 on extension shaft 27', a braking member 66 opposite said disk, and an operating arm 64 on the rock shaft 63 which

controls the slidable sleeve or cone 67 for clutch 27.

What we claim, is:

1. A wash tray having a plurality of compartments, in combination with a wringer mounted to move lengthwise over the top of said tray and arranged obliquely to the front 40 of the tray.
2. A laundry apparatus, comprising a compartmented receptacle, a wringer movable lengthwise of said receptacle, a motor operatively connected with said wringer, and controlling means for said motor and wringer comprising a treadle having a 45 pedal extending lengthwise at the front side of said receptacle, whereby the operator standing in front of any compartment may start and stop the wringer even though the latter may be situated adjacent another distantly located compartment.
3. A laundry apparatus, comprising a wash tray having a plurality of compartments therein, and a wringer supported to 50 roll upon the parallel upper edges of the rear and front walls of said tray, in combination with a supporting frame for said tray, a motor mounted upon said frame provided with operating connections for said 55 wringer at the rear of said tray, and a controlling pedal mounted upon said frame and extending the full length thereof opposite all of said compartments.

In testimony whereof we affix our signatures.
